United States Patent

Des. 239,754
Patented May 4, 1976

239,754

CUP

Warren A. Yoder, 238 Hayes Ave.,
Cottage Grove, Oreg. 97424

Filed Nov. 5, 1973, Ser. No. 413,035

Term of patent 14 years

Int. Cl. D7—01

U.S. Cl. D7—9

FIG. 1

FIG. 2

FIG. 3

FIG. 4

FIG. 5

FIG. 1 is a top plan view of a cup showing my new design;

FIG. 2 is a bottom plan view thereof;

FIG. 3 is an elevational view of the cup;

FIG. 4 is a vertical sectional view of the cup taken on the line 4—4 of FIG. 1; and

FIG. 5 is a vertical sectional view taken on the line 5—5 of FIG. 1.

I claim:

The ornamental design for a cup, as shown.
